UNITED STATES PATENT OFFICE.

JAMES G. BAILEY, OF KNOXVILLE, TENNESSEE.

STOP MOTION FOR SEWING MACHINES.

1,407,367.

Specification of Letters Patent. Patented Feb. 21, 1922.

Application filed February 25, 1921. Serial No. 447,645.

To all whom it may concern:

Be it known that I, JAMES G. BAILEY, a citizen of the United States, residing at Knoxville, in the county of Knox and State 5 of Tennessee, have invented a new and useful Improvement in Stop Motions for Sewing Machines, of which the following is a specification, reference being had to the accompanying drawing.

10 This invention relates to a stop motion attachment for sewing machines adapted particularly for machines employing a plurality of threads and the object of the invention is to provide a simple attachment which

15 may be placed on any of the machines now in use and in which a single clutch mechanism may be operated by any one of a plurality of thread controlling devices. These are so arranged that a knot or other obstruction

20 in the thread will co-act with the attachment to cause the shifting of a clutch so that the shaft of the machine is released from the pulley to permit the machine to come to rest, and thereby prevent the knot from reaching

25 and breaking the needle, and causing replacement of the same, and also permitting damage to the article or the goods being stitched.

The invention consists in the construction, 30 arrangement and combination of parts hereinafter more particularly described and then definitely claimed.

In the drawings:

Figure 1 shows a plan view of part of a 35 sewing machine of a well known type, with my invention applied thereto.

Figure 2 is a section through the line 2—2 of Figure 1.

Figure 2^a is a section through the line 40 2^a—2^a of Figure 2.

Figure 3 is a section through the line 3—3 of Figure 1.

Figure 3^a is a section through the line 3^a—3^a of Figure 3.

45 Figure 4 is a rear elevation of the machine and attachment.

Figure 5 is an upright transverse section on the line 5—5 of Figure 4.

Figure 6 is a view of the latch holding 50 the parts in locked position.

Figure 7 is a view similar to Figure 5 but with a knot caught and with the thread being drawn to stop the machine.

55 Figure 8 is a view of the latch after it is released or opened.

Figure 9 is a front view of part of the attachment.

Figure 10 is an end elevation looking from the left.

Figure 11 is a transverse section through 60 the yoke and connected parts.

Figures 12 and 13 are sectional details.

Figure 14 is a rear perspective view of the attachment detached.

Figure 15 is a perspective view of a modification.

Figure 16 is a top plan view of the same.

Figure 17 is a plan view of a detail.

Figure 18 is a sectional view through the line 18—18 of Figure 16. 70

Referring now to the details of the drawings by letters: A is the frame of a sewing machine which may be of any desired character but which, in the embodiment illustrated, is the Willecox & Gibbs multiple 75

thread machine, having a main shaft B, operated by a loose pulley C with which co-operates any desired form of clutch D (shown in conventional form), the latter arranged to be thrown on and off by means of 80 a clutch lever E. In the form shown this clutch lever E is pivoted at E¹ to the arm F (Figure 14) and it has a yoke E² co-operating with a movable clutch ring D¹ of the clutch D so that when the yoke E² is thrown 85

in the direction of the arrow in Figures 1 and 14, the clutch is thrown to release the pulley from shaft B to stop the machine, the throwing of the clutch being in this case accomplished by pressure of the yoke, E², left- 90

ward against the clutch ring, D¹, whereby said ring is pressed leftward for disengaging the pulley, C, from the main shaft, B. When the yoke, E², has thus been shifted leftward, it continues to bear against the clutch ring 95

and thereby serves as a friction brake to stop the main shaft, said clutch ring being in engagement with a clutch member which is immovably secured to the main shaft. For a detail description of such a clutch, I refer to 100 my application, Serial No. 456,415, filed by me March 28, 1921, for Letters Patent of the United States for an improvement in clutches. Said clutch lever E is pivotally carried by any suitable support, but as shown 105

by an arm F forming part of a horizontal frame member F¹ and the latter may be supported, for example, by means of two standards G and G¹.

Said standards, in the embodiment illus- 110

- trated, are connected by means of a horizontal brace G^2 , and they form a support for the other parts shown in Figure 14, such, for example, as the longitudinally movable 5 rod H which is jointed to the clutch lever E and is designed to operate the clutch, when released, an expansion coiled spring I being employed which tends to normally move the rod H in the direction of the arrow in Figure 14, said spring acting, for example, between the said standard G and a collar H^2 on said rod H . The rod H is preferably provided with a handle such as shown at H^3 .
- 10 In order to hold the parts in the positions shown in Figures 1, 4, 6 and 14, where the spring I is under compression and the clutch D is locked to the pulley C so that the machine is being operated, said rod H is provided with a latch arm or finger H^4 which projects outwardly therefrom under a pivoted latch J having on its under face a lug J^1 normally extending into the path of the latch arm or finger H^4 . When this 15 latch J is moved upwardly to release the latch arm H^4 , the spring I is permitted to push the rod H longitudinally in the direction of the arrow in Figure 14 to move the clutch lever E on its pivot E^1 to shift the 20 clutch and release it from the pulley C , whereupon the latter is free to rotate with respect to the clutch and its shaft H so that the latter is no longer rotated, and the machine comes to a stop.
- 25 30 35 The said latch J has a latch lug J^1 and is pivoted at J^2 to a block as J^3 mounted on the frame bar F^1 and the upper face of this block J^3 also serves as a support upon which the rear part of the latch arm H^4 may rest and slide. To said block J^3 is also fixed an upper horizontal guide bar J^4 which is spaced from the block J^3 far enough to permit the latch arm H to slide under it. Thus the latch arm slides upon the block J^3 and 40 is prevented from any vertical movement by the spaced guide bar J^4 . The free end of the latch J is connected by a wire link J^5 to an arm K^1 (weighted at K^2) forming part of a horizontal yoke K pivoted at K^3 to the 45 frame members L and L^1 rising from the horizontal frame members F^1 (Figures 1, 4, 11 and 14), the upper ends of said members L and L^1 being connected by a horizontal shaft M . Upon said shaft M are pivotally 50 supported one or more thread guiding bars N which project downwardly from said shaft M and normally rest upon the frame member F^1 . Each of the upper rear ends of said thread guiding bars N has a finger 55 N^1 and said fingers are positioned to bear upon the aforesaid yoke K when the lower free end of any of said bars is raised. It follows that should any one of said thread 60 guiding bars N be lifted, its rear finger N^1 is caused to move downward (Figure 5) and press against the yoke K , thus causing the latter to rock on its pivots K^3 for the lifting of its arm K^1 to draw upwardly the wire J^5 to lift the latch J and thereby release the rod H endwise and thereby shift the clutch. These pivoted bars N all normally hang downward by gravity and rest upon the horizontal frame member F^1 as shown in Figure 5 and there are as many of the bars N as 70 there are threads T used in the machine, and they are intended to be lifted or raised should any of the threads T have a knot or any other obstruction which, if allowed to pass to the needle, would break or damage 75 the same. To this end, the thread or threads before passing to the needle or needles all pass under a bar as O having separating fingers O^1 and then through notches or slits P^1 in a thread bar P . This bar O and the 80 thread bar P are supported on a horizontal plate Q which is in turn supported on the upper end of the standard G^1 and on a brace G^3 . The notches or slits in said thread bar P are just the proper size to permit a thread 85 to pass through the same without any undue friction but should any of the threads have a knot, T^1 , (Fig. 5) therein, it would be too large to pass through the slit of the thread bar P . The rear part of the thread bar P 90 is rounded as shown at P^2 in Figure 2^a to prevent the cutting of the thread as it passes downward. From this thread bar P , the thread or threads pass downwardly and through eyes or loops N^2 on the lower ends 95 of the aforesaid pivoted bars N , and after passing therethrough, the thread or threads pass up to a second thread bar R also mounted on the plate Q and through slits or openings R^1 therein and from thence to 100 the tension device (not shown) and finally to the needle or needles. Said second thread bar R has its front part rounded at R^1 (Figure 3^a) to prevent cutting of the thread. It will be manifest that should one of the 105 threads have a knot therein, as shown in Figure 7, the part of the thread having the knot will be caught by the thread bar P and held against movement. Hence as the other end of the thread is being continually 110 drawn forward by the needle and feed mechanism, it follows that the thread between the needle and the knot against the thread bar P will become shorter, thus drawing upwardly the free end of its pivoted thread 115 bar N to the point shown in Figure 7. This movement causes the rear finger N^1 of the appropriate bar N to press downward upon the yoke K for the tilting of the latter as already described, whereby the latch mechanism is operated for the release of the 120 rod H .
- In operation, assuming that the thread or threads have been properly run through my attachment to the needle or needles, all that 130

- it is necessary to do in order to start the machine is for the operator to pull the handle H^3 against the tension of the spring I . This slight movement of said handle 5 moves the clutch lever E and the yoke E^2 so as to connect the loose pulley C to the clutch and the machine then automatically starts, the pulley being in constant operation.
- 10 The thread or threads will now pass through my attachment and the machine will run continuously, so far as the attachment is concerned, unless one of the threads has a knot or some other obstruction too 15 large to pass through its appropriate slit in the thread bar P . When such a knot moves against said thread bar P , that part of the thread will be prevented from further movement, but the machine will continue to draw 20 the other end of the thread so that the thread between the needle and the thread bar P becomes shorter, thus drawing the appropriate pivoted bar N from the position shown in Figure 5 to the position shown in 25 Figure 7. This movement of the pivoted bar N will cause its finger N^1 to move against the yoke K drawing upon the wire J^4 as hereinafter described and lifting the pivoted latch J from the position shown in 30 Figure 6 to that shown in Figure 8, so that the spring I compels the rod H to move in the direction of the arrow shown in Figures 1 and 14, thereby moving the clutch lever E to throw the clutch yoke E^2 to release the clutch 35 D from the constantly rotating pulley C . Thus the machine will be allowed to stop so that the knot may be removed and the needle re-threaded, and the knot never reach the needle to break the same and possibly 40 damage the goods being sewed.
- As above stated, the yoke, E^2 , performs the double function of disengaging the clutch and of pressing against the clutch ring D^1 , so as to instantly exert a brake action for 45 stopping the main shaft, such action over-coming momentum in said shaft and in moving parts connected to said shaft.
- Regarding the latch mechanism, it is to be further observed that each thread guiding 50 bar, N , is a hinged gravity member in the form of a lever having its long arm engaged by a thread for guiding the thread and for lifting the long arm of said member when the forward movement of the thread 55 is arrested by the relatively stationary thread guiding bar, P , and as shown by the drawings, the short arm of said lever or gravity member is much shorter than the long arm and it makes engagement with the 60 yoke, K , for moving the yoke. Therefore, when the forward movement of the thread is arrested and the part of the thread between the bar, P , and the needle is shortened by the action of the needle and the feed 65 members, the effect of the strain transmit-ted through said part of the thread for the lifting of the lever or gravity member, N , is multiplied in proportion to the length of the long arm to the length of the short arm of the lever. Furthermore, the thread is so applied to the lever, N , as to cause a doubling of the effect of the strain of the thread for lifting said long arm. For the thread is held stationary at the bar, P , and is drawn upward only at the bar, R . Thus the 70 eye, N^2 , is lifted as though it were a pulley similarly hung by a rope only half as fast as the thread moves upward to the thread guiding bar, R . These two means of amplifying the effect of the thread strain are im- 75 portant, because reliable action of the latch mechanism results.
- From the foregoing and the accompanying drawings it will be seen that I have invented a simple attachment which may be 80 easily applied to machines now in use, in which provision is made for either one or a plurality of threads all of which are arranged to operate a common latch to release the single clutch throwing lever and prevent 85 a knot in the thread from reaching the needle to break or damage the same and thus necessitate the replacing of the needle and also avoiding injury to the goods being sewed. 90
- Manifestly the same mechanism may be made a part of a new machine, and, in fact the claims are not limited to the mechanism shown. For instance, other forms of latch mechanism may be employed, and as one instance I would refer to the construction 95 shown in Figures 15 to 18 inclusive. In these figures, the yoke K may be operated by the pivoted bars N in identically the same manner as the yoke K in the other 100 figures of the drawing, but instead of having the wire J^5 , the yoke K is provided with a horizontal arm K^4 shown in Figures 15 and 17, and directed toward the clutch end 105 of the machine. The end of this arm K^4 is 110 constructed and arranged to co-act with an arm K^5 projecting horizontally from an upright rock shaft K^6 , the construction being such that when the parts are in the position shown in Figure 15, the arm K^5 will 115 engage the arm K^4 and the parts will be held in their normal positions. When, however, the yoke K is actuated as hereinbefore described, the arm K^4 is elevated to release the arm K^5 and permit it to be moved with 120 its rock shaft K^6 . The lower end of said rock shaft K^6 is journaled in a block K^7 somewhat similar to the block J^3 of Figure 14 and said rock shaft K^6 is furthermore provided with two arms K^8 and K^9 . Co- 125 acting with these arms is an arm H^5 projecting from the spring operated rod H , the latter being identical with that shown in Figures 1 to 14. When the device is to be 130 "set", the operator draws the rod H in the

direction opposite to the arrow in Figures 15 and 16 whereby the arm H^s will be caused to strike against the arm K^s and oscillate the rock shaft K^e so that the arm 5 K^4 will interlock with the arm K^s and hold the parts latched in the position shown in Figure 15. The spring pressed rod H having a tendency to move in the direction of the arrows in Figures 15 and 16 is held from 10 movement by reason of the fact that its arm H^s cannot move since it is held by the shoulder K^{10} on the arm K^s and the latter and its rock shaft K^e are held immovable by the interlocking of the arms K^4 and K^s . However, 15 as soon as the yoke K is operated by a knot in the thread, to lift the arm K^4 , the arm K^s of the vertical rock shaft K^e is released, thus permitting the spring to move the rod H toward the right as viewed in Figure 16, 20 the arm H^s of said rod H pushing the arm K^s clockwise or to the position shown in dotted lines in Figure 16 until contact is made with the stop post K^{11} . When it is desired to re-set the device the operator, as 25 above stated, merely moves the rod H in the direction opposite to the arrows, whereupon the arm H^s engages the arm K^s and hence the rock shaft K^e and all the parts supported thereby are turned contra-clockwise into the position shown in Figure 16, 30 such movement being far enough to again permit the interlocking of the arms K^4 and K^s .

Other modifications may of course be 35 employed and where, in the following claims, I use the expression "latch mechanism", I intend to cover any mechanism intervening the spring operated bar and the threads, whereby when the movement of the 40 thread is arrested to shorten the thread, the latch mechanism is actuated to permit the spring-operated rod to shift the clutch.

I claim as my invention,

1. In a sewing machine and in combination with the clutch thereof, an endwise slidable rod, a spring tending to slide said rod endwise in one direction, a latch mechanism applied to said rod between its ends and comprising movable members and a stationary member adapted to make engagement with an obstruction or enlargement on the thread whereby the thread is shortened between the needle and said stationary member to actuate said movable members, substantially as described.

2. In a sewing machine and in combination with the clutch thereof, an endwise slidable rod, a spring tending to slide said rod endwise in one direction, a latch mechanism 60 applied to said rod between its ends and comprising movable members and a stationary member having passages adapted to permit threads to freely pass through the same and constructed to arrest the movement of the thread if a knot or other enlargement in 65

the thread moves against said stationary member, thereby shortening the thread and operating said movable members, substantially as described.

3. In a sewing machine and in combination with the clutch thereof, an endwise slid- 70 able rod, a spring tending to slide said rod endwise in one direction, a latch mechanism applied to said rod between its ends and comprising movable members and a stationary member adapted to engage and hold an obstruction or enlargement of the thread, whereby, by the action of the sewing mechanism, the thread is shortened between the needle and said stationary member to 80 actuate said movable members, substantially as described.

4. In a sewing machine and in combination with the clutch thereof, a latch mechanism in operative relation with said clutch 85 and comprising a stationary member constructed and adapted to guide thread and to engage an obstruction or enlargement of the thread whereby the thread is shortened between the needle and latch mechanism, said mechanism also including a hinged member guiding the thread and movable by the shortening of the thread to actuate said latch, substantially as described.

5. In a sewing machine and in combination with the clutch thereof, a latch mechanism in operative relation with said clutch and comprising a stationary member having 95 passages adapted to permit threads to freely pass through the same and constructed to 100 arrest the movement of the thread if a knot or other enlargement moves against said stationary member, thereby shortening the thread, said mechanism also including a hinged member guiding the thread and movable by the shortening of the thread to operate the latch, substantially as described.

6. In a sewing machine and in combination with the clutch thereof, a latch mechanism in operative relation with said clutch 110 and comprising a substantially fixed member having passages adapted to permit threads to freely pass through the same and constructed to arrest the movement of the thread if a knot or other enlargement moves 115 against said latch mechanism, thereby shortening the thread, and a hinged member guiding the thread and movable by the shortening of the thread for operating the latch, substantially as described.

7. In a sewing machine and in combination with the clutch thereof, an endwise slid- 120 able rod, a spring tending to slide said rod endwise in one direction, a latch mechanism applied to said rod between its ends 125 and comprising a stationary member constructed and adapted to engage an obstruction or enlargement of the thread, whereby the thread is shortened between the needle and said stationary member, said mechanism 130

also including a shiftable latch member movable by the shortening of the thread to actuate said shiftable member, substantially as described.

- also including a shiftable latch member movable by the shortening of the thread to actuate said shiftable member, substantially as described.

5. 8. In a sewing machine and in combination with the clutch thereof, an endwise slideable rod, a spring tending to slide said rod endwise in one direction, a latch mechanism applied to said rod between its ends and having in a stationary member a passage adapted to permit thread to freely pass through the same and constructed to arrest the movement of the thread if a knot or other enlargement moves against said stationary member, thereby shortening the thread, said mechanism also including a shiftable latch member movable by the shortening of the thread to actuate said shiftable member, substantially as described.

10. 9. In a sewing machine and in combination with the clutch thereof, a latch mechanism in operative relation with said clutch and constructed and adapted to be actuated through engagement by an obstruction or enlargement of the thread whereby the thread is shortened between the needle and latch mechanism, said mechanism also including a shiftable latch and a hinged gravity operating member controlling said latch and guiding the thread and movable by the shortening of the thread to actuate the latch, substantially as described.

15. 10. In a sewing machine and in combination with the clutch thereof, a latch mechanism in operative relation with said clutch and having a passage adapted to permit thread to freely pass through the same and to arrest the movement of the thread if a knot or other enlargement moves against said latch mechanism, thereby shortening the thread, said mechanism also including a shiftable latch, and a hinged gravity operating member controlling said latch and guiding the thread and movable by the shortening of the thread to actuate the latch, substantially as described.

20. 11. In a sewing machine and in combination with the clutch thereof, a latch mechanism in operative relation with said clutch and constructed and adapted to be actuated through engagement by an obstruction or enlargement of the thread whereby the thread is shortened between the needle and latch mechanism, said mechanism also including a shiftable latch, a yoke and weighted lever cooperating with said latch, and a hinged gravity operating member controlling said yoke and latch and guiding the thread and movable by the shortening of the thread to actuate the yoke and latch, substantially as described.

25. 12. In a sewing machine and in combination with the clutch thereof, a spring operated, endwise slideable rod controlling said clutch, a latch mechanism in operative relation with said rod and having a stationary member in which are passages adapted to permit threads to freely pass through the same and constructed to arrest the movement of the thread if a knot or other enlargement moves against said stationary member, thereby shortening the thread, said mechanism also including a hinged member movable by the shortening of the thread to operate the latch to release said rod, substantially as described.

30. 13. In a sewing machine and in combination with the clutch thereof, a spring operated, endwise slideable rod controlling said clutch, a latch mechanism in operative relation with said rod and comprising a substantially fixed member having passages adapted to permit threads to freely pass through the same and constructed to arrest the movement of the thread if a knot or other enlargement moves against said fixed member, thereby shortening the thread, and a hinged member movable by the shortening of the thread for operating the latch to release said rod, substantially as described.

35. 14. In a sewing machine and in combination with the clutch thereof, a spring operated, endwise slideable rod controlling said clutch, a latch mechanism in operative relation with said rod and comprising a stationary means constructed and adapted to guide individual threads and to engage an obstruction or enlargement of the thread whereby the thread is shortened between the needle and latch mechanism, said mechanism also including a shiftable latch movable by the shortening of the thread to actuate the same to release said rod, substantially as described.

40. 15. In a sewing machine and in combination with the clutch thereof, a spring operated, endwise slideable rod controlling said clutch, a latch mechanism applied to said rod between its ends and comprising stationary means constructed and adapted to guide individual threads and to engage an obstruction or enlargement of the thread whereby the thread is shortened between the needle and latch mechanism, said mechanism also including a shiftable latch movable by the shortening of the thread to actuate the same to release said rod, substantially as described.

45. 16. In a sewing machine and in combination with the clutch thereof, a spring operated, endwise slideable rod controlling said clutch, a latch mechanism applied to said rod between its ends and comprising a stationary member having passages adapted to permit threads to freely pass through the same and constructed to arrest the movement of the thread if a knot or other enlargement moves against said latch mechanism, thereby shortening the thread, said mechanism also including a shiftable latch movable by the shortening of the thread to operate the latch to release said rod, substantially as described.

50. 17. In a sewing machine and in combination with the clutch thereof, a spring operated, endwise slideable rod controlling said clutch, a latch mechanism applied to said rod between its ends and comprising a stationary member having passages adapted to permit threads to freely pass through the same and constructed to arrest the movement of the thread if a knot or other enlargement moves against said latch mechanism, thereby shortening the thread, said mechanism also including a shiftable latch movable by the shortening of the thread to operate the latch to release said rod, substantially as described.

55. 18. In a sewing machine and in combination with the clutch thereof, a spring operated, endwise slideable rod controlling said clutch, a latch mechanism applied to said rod between its ends and comprising a stationary member having passages adapted to permit threads to freely pass through the same and constructed to arrest the movement of the thread if a knot or other enlargement moves against said latch mechanism, thereby shortening the thread, said mechanism also including a shiftable latch movable by the shortening of the thread to operate the latch to release said rod, substantially as described.

60. 19. In a sewing machine and in combination with the clutch thereof, a spring operated, endwise slideable rod controlling said clutch, a latch mechanism in operative relation with said rod and comprising a stationary member having passages adapted to permit threads to freely pass through the same and constructed to arrest the movement of the thread if a knot or other enlargement moves against said stationary member, thereby shortening the thread, said mechanism also including a hinged member movable by the shortening of the thread to operate the latch to release said rod, substantially as described.

65. 20. In a sewing machine and in combination with the clutch thereof, a spring operated, endwise slideable rod controlling said clutch, a latch mechanism in operative relation with said rod and comprising a stationary member having passages adapted to permit threads to freely pass through the same and constructed to arrest the movement of the thread if a knot or other enlargement moves against said stationary member, thereby shortening the thread, said mechanism also including a hinged member movable by the shortening of the thread to operate the latch to release said rod, substantially as described.

shortening of the thread to actuate the same to release said rod, substantially as described.

17. In a sewing machine and in combination with the clutch thereof, a spring operated, endwise slidable rod controlling said clutch, a latch mechanism in operative relation with said rod and constructed and adapted to be actuated through engagement by an obstruction or enlargement of the thread whereby the thread is shortened between the needle and latch mechanism, said mechanism also including a shiftable latch, a yoke and weighted lever cooperating with said latch, and a gravity operating hinged member controlling said yoke and latch and guiding the thread and movable by the shortening of the thread to actuate the yoke and latch to release said rod, substantially as described.

18. In a sewing machine and in combination with the clutch thereof, a spring operated, endwise slidable rod controlling said clutch, a latch mechanism in operative relation with said clutch and having passages adapted to permit threads to freely pass through the same and constructed to arrest the movement of the thread if a knot or other enlargement moves against said latch mechanism thereby shortening the thread, said mechanism also including a shiftable latch, a yoke, and a weighted lever cooperating with said latch, and a gravity operating hinged member controlling said yoke and latch and movable by the shortening of the thread to actuate the yoke and latch to release said rod, substantially as described.

19. In a sewing machine and in combination with the clutch thereof, a latch mechanism in operative relation with said clutch and comprising a thread bar with a passage permitting free passage of the thread but constructed to arrest the movement of the thread if a knot or other enlargement moves against said thread bar, a hinged member operatively connected with the latch and constructed to guide the thread, and a second thread bar to guide the thread after it leaves said hinged member, substantially as described.

20. In a sewing machine and in combination with the clutch thereof, a latch mechanism in operative relation with said clutch and comprising a thread bar with a passage permitting free passage of the thread but constructed to arrest the movement of the thread if a knot or other enlargement moves against said thread bar, a hinged member constructed to guide the thread, a yoke in operative relation with the latch and said hinged member, and a second thread bar to guide the thread after it leaves said hinged member, substantially as described.

21. In a sewing machine and in combination with the clutch thereof, a spring oper-

ated, endwise slidable rod, a latch mechanism in operative relation with said rod for controlling said clutch, said latch mechanism comprising a thread bar support, a thread bar seated on said support and having a passage permitting free passage of the thread but constructed to arrest the movement of the thread if a knot or other enlargement moves against said thread bar, a hinged member operatively connected with the latch and constructed to have the thread engage the same, and a second thread bar on said support and serving to guide the thread after it leaves said movable member, substantially as described. 80

22. In a sewing machine and in combination with the clutch thereof, a latch mechanism operating relatively with said clutch and comprising a shiftable latch, a supporting plate, a slotted thread guiding bar thereon, a gravity operating member under said support, a N-form yoke connected with said shiftable latch and operated by said gravity member, and a second thread guiding bar carried by said plate, substantially as de- 90

23. In a sewing machine and in combination with the clutch thereof, a latch mechanism operating relatively with said clutch and comprising a shiftable latch, a supporting plate, a slotted thread guiding bar thereon, a gravity operating member under said support, a yoke connected with said shiftable latch and operated by said gravity member, and a second thread guiding bar carried by said plate, each of said thread guiding bars having rounded parts to prevent cutting the thread, substantially as described. 95

24. In a sewing machine and in combination with the clutch thereof, a spring-actuated, endwise slidable rod connected with said clutch, a latch mechanism in operative relation with said rod and comprising a shiftable latch, a supporting plate, a slotted thread guiding bar thereon, a gravity operating member under said support, a yoke connected with said shiftable latch and operated by said gravity member, and a second thread guiding bar carried by said plate, substantially as described. 105

25. In a sewing machine and in combination with the clutch thereof, a spring-actuated, endwise slidable rod in operative relation with said clutch, a latch mechanism in 120 operative relation to said rod and comprising a shiftable latch, a supporting plate, a slotted thread guiding bar thereon, a gravity operating member under said support, a yoke connected with said shiftable latch and operated by said gravity member; and a second thread guiding bar carried by said plate, each of said thread guiding bars having rounded parts to prevent cutting the thread, substantially as described. 125 130

26. In a sewing machine and in combination with the clutch thereof, a latch mechanism in operative relation with said clutch and comprising a latch and a plurality of hinged members, each constructed to operate said clutch if a knot or enlargement arrests the movement of the thread, said latch being released by the movement of any one of said plurality of hinged members to effect the operation of said clutch, substantially as described.
27. In a sewing machine and in combination with the clutch thereof, a latch mechanism in operative relation with said clutch and comprising a shiftable latch and a plurality of hinged members, each constructed to operate said latch if a knot or enlargement arrests the movement of the thread, said latch being shifted and released by the movement of any one of said plurality of hinged members to effect the operation of said clutch, substantially as described.
28. In a sewing machine and in combination with the clutch thereof, an endwise slidable rod, a spring tending to slide said rod endwise in one direction, a latch mechanism applied to said rod between its ends and comprising a relatively stationary thread bar having a plurality of passages therein to permit threads to freely pass through said passages and constructed to arrest any of said threads if a knot or enlargement moves against said bar, all of said threads affecting the single latch if any one of them is obstructed, substantially as described.
29. In a sewing machine and in combination with the clutch thereof, a latch mechanism in operative relation with said clutch and comprising a plurality of hinged members, each constructed to operate said clutch, a relatively stationary thread bar having a plurality of passages permitting the threads to freely pass through the same but arranged to arrest the thread if a knot or enlargement moves against said thread bar whereby the thread is shortened and its appropriate hinged member is operated to release said latch, substantially as described.
30. In a sewing machine and in combination with the clutch thereof, a spring operated, endwise slidable rod controlling said clutch, a spring tending to slide said rod endwise in one direction, a latch mechanism in operative relation with said rod and comprising a shiftable latch and a plurality of hinged members, each constructed to operate said latch if a knot or enlargement arrests the movement of the thread, said latch being shifted and released by the movement of any one of said plurality of hinged members to effect the operation of said clutch, substantially as described.
31. In a sewing machine and in combination with the clutch thereof a spring oper-
- ated, endwise slidable rod controlling said clutch, a spring tending to slide said rod endwise in one direction, a latch mechanism in operative relation with said rod and comprising a relatively stationary thread bar having a plurality of passages therein to permit threads to freely pass through said passages and constructed to arrest any of said threads if a knot or enlargement moves against said member, any of said threads affecting the latch if any one of them is obstructed, substantially as described.
32. In a sewing machine and in combination with the clutch thereof, a spring operated, endwise slidable rod controlling said clutch, a spring tending to slide said rod endwise in one direction, a latch mechanism in operative relation with said rod and comprising a plurality of hinged members, each constructed to operate said clutch, a relatively stationary thread bar having a plurality of passages permitting the threads to freely pass through the same but arranged to arrest the thread if a knot or enlargement moves against said thread bar whereby the thread is shortened and its appropriate movable member is operated to release the latch, substantially as described.
33. In a sewing machine and in combination with a clutch, a latch in operative relation with said clutch, a spring held under restraint when the latch is engaged, a plurality of hinged members all co-acting with said latch and arranged to release the same if any of said members is moved, and a relatively stationary thread bar having a plurality of passages guiding threads to said members and arranged to arrest any of said threads if a knot or obstruction moves against the thread bar whereby the arrested thread is shortened to lift its appropriate hinged member to release said latch, substantially as described.
34. In a sewing machine and in combination with a clutch, a shiftable latch in operative relation with said clutch, a spring held under restraint when the latch is engaged, a plurality of hinged members all co-acting with said latch and arranged to shift and release the same if any of said members is moved, and a relatively stationary thread bar having a plurality of passages guiding threads to said members and arranged to arrest any of the threads if a knot or obstruction moves against the thread bar whereby the arrested thread is shortened to lift its appropriate hinged member to release said latch, substantially as described.
35. In a sewing machine and in combination with a clutch, a spring operated, endwise slidable rod controlling said clutch, a spring tending to slide said rod endwise in one direction, a latch in operative relation with said rod, a plurality of members all co-acting with said latch and arranged to re-
